PIETRO P. VESCOVI, OF OTTAWA, KANSAS.

PORTABLE FIRE-ESCAPE.

1,352,230.

Specification of Letters Patent. Patented Sept. 7, 1920.

Application filed May 9, 1919. Serial No. 295,842.

To all whom it may concern:

Be it known that I, PIETRO P. VESCOVI, a subject of the King of Italy, residing at Ottawa, in the county of Franklin and State 5 of Kansas, have invented certain new and useful Improvements in Portable Fire-Escapes; and I do declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 This invention relates to portable fire-escapes and one of the objects thereof is to provide means capable of being confined within a relatively small compass adapted to be conveniently and expeditiously set up 20 for use in effecting the escape of a person from a building, the mechanism being such that the device is under the control of a descending person at all times so as to eliminate the liability of accidents.

25 The invention broadly contemplates the provision of means for normally confining a wound flexible member upon a spindle within a drum or casing in such manner that one end of the flexible member may be 30 anchored to a suitable support within a room or building so as to permit the flexible member to be gradually unwound as the person descends, the unwinding being resisted by friction induced by the weight 35 of the descending person, the friction being in proportion to the weight sustained and there being an auxiliary braking device for varying the friction exerted against the flexible member, the latter being under the 40 direct control of the descending person.

Other objects and advantages of the invention will be referred to hereinafter, it being understood that changes in form, proportion and minor details of construction 45 may be resorted to without departing from the spirit of the invention or sacrificing any of its advantages.

In the drawings, Figure I is a perspective view of the device ready for use.

50 Fig. II is a vertical sectional view through the same, and

Fig. III is a detail view of the manually operated brake mechanism.

The casing or braking drum consists of a 55 main casing member 1 and a cover 2, the cover being adapted to be secured by fastening devices 4 and 5. The member 1 is pro-

vided with a slit 6 through which a flexible member, such as a steel tape or the like, may pass and surrounding said slit and secured to the periphery of the member 1 is a substantially rectangular box or tubular member 7, the inner surface of one end of which is faced with a braking material or fabric 8 to coöperate with a pivoted braking member 9 on the pivot 10, extending transversely of the box 7, the braking member 9 having an upwardly extending and laterally curved dog or engaging projection 11 adapted to bear against the flexible member 12 to engage it in such manner that slippage will be prevented, as will be explained hereinafter. The lower end of the braking member 9 is provided with a braking facing 12 adapted to engage against the side of the flexible member or tape and assist in binding the same between the faces 12 and 8 and the amount of friction exerted against the flexible member may be determined by an adjustable set screw 13 which extends 80 through a threaded opening 14 in the end 15 of the box 7.

Within the casing formed by the members 1 and 2 is a coiled flexible member, preferably a steel tape, which is fast on a mandrel 85 or winding drum 16 having outwardly projecting trunnions 17 and 18 which project through the alining elongated slots 19 and 20 in the members 1 and 2, and within the flange 3, preferably at the lower portion 90 thereof, is a braking wear surface 21 against which the periphery of the coiled flexible member may bear. The outer end of the flexible member is provided with a loop 22, by means of which the device may be 95 fastened to a suitable anchoring medium in a room or building, preferably a hook if one is available and if not, any means suitable for the purpose intended. The trunnion members which project through the 100 slots 19 and 20 are engaged by a suspension yoke 23 which is provided with side bars 24 and 25 having eyes or openings 26 and 27 to engage the trunnions and said yoke is adapted to support a suitable swing or 105 chair which serves as a carrier for the descending person. 28 is a crank having threaded engagement with one of the trunnions whereby the flexible member or tape may be wound upon its mandrel to prepare 110 the device for use.

Assuming all the parts to be properly assembled and assuming that it is desired to use the device, the free end of the flexible

- member may be attached to a suitable anchor and the tape-carrying mechanism with the swing for supporting the person may be placed on the outside of the building. The 5 person then suspends himself, by means of the sling or other support, and starts to descend. Since the winding drum and the trunnions are guided in the alining slots in the members 1 and 2, the weight exerted 10 in a downward direction will cause friction between the periphery of the flexible member and the brake lining on the flange 3 so that the unwinding of the tape will be resisted in proportion to the weight of the descending 15 person. The descent can not begin, however, until the device is slightly tipped because the pawl on the auxiliary braking device will impinge against the tape since its engaging end is out of line with and beyond the slit 20 in flange 3 through which the tape projects. In order to start descending, it will be necessary to slightly tip the drum so as to release engagement of the pawl end of the braking device from contact with the tape. It 25 is not intended that the friction caused by the weight of the person will be sufficient to entirely prevent the unwinding of the tape but the unwinding control is accomplished by means of the manually operated 30 screw, which controls the amount of friction produced by the binding of the tape between the faces 8 and 12 and since the manually operated screw (or brake tensioning device) is within easy reach of the operator, it is obvious that the speed at which 35 the person descends may at all times be under his control and that the speed may be varied by manipulating the screw in the box 7.
- 40 From the foregoing it will be apparent that the device is simple in operation, easily constructed, inexpensive of manufacture and that the entire mechanism may be normally maintained within a relatively small compass so as to render it conveniently portable but at the same time, ready for instant use.
- What I claim and desire to secure by Letters-Patent is:
1. A fire escape comprising a casing having a braking face therein and provided with an opening, a flange about the opening, a flexible connection coiled within the casing, the periphery of which is adapted to bear against the braking face, a drum upon which the flexible connection is wound, trunnions on the drum projecting through alining, elongated slots in the casing, a braking face rigid with the flange surrounding the opening, a pivoted braking member adjacent to the braking face on the flange and having a curved portion engaging the flexible connection, and a yoke carried by the trunnions.
  2. A fire escape comprising a casing having a braking face therein, a flexible con-

nexion coiled within the casing, the periphery of which is adapted to bear against the braking face, a drum upon which the flexible connection is wound, trunnions projecting through alining elongated slots in the casing, and a suspension yoke suspended from said trunnions.

3. A fire escape comprising a casing having a braking face therein, a flexible connection coiled within the casing, the periphery of which is adapted to bear against the braking face, a drum upon which the flexible connection is wound, trunnions projecting through alining elongated slots in the casing, a suspension yoke suspended from said trunnions, and an auxiliary manually-controlled braking device for exerting pressure against the flexible connection, said device being carried exteriorly of the casing.

4. A fire escape comprising a cylindrical casing having a braking face therein and provided at opposite sides with elongated slots, a coiled flexible connection within said casing, the periphery of which bears against the braking face in the casing, a winding drum adapted to have sliding movement within the confines of the slots, a sling suspended from said winding drum, and means exteriorly secured to the casing for effecting a braking action against said flexible connection.

5. A portable fire escape comprising a cylindrical casing having a braking face therein and provided at its sides with elongated slots, a winding drum, the ends of which project through the slots, a coiled tape normally within the casing and having one end connected to the winding drum, the other end projecting through a slit in the casing, a box surrounding the slit in the casing and having a braking surface, a pivoted braking member coöperating with the braking surface and carried by the box, and manually controlled means for actuating said braking member.

6. A portable fire escape comprising a cylindrical casing having a braking face therein and provided at its sides with elongated slots, a winding drum, the ends of which project through the slots, a coiled tape normally within the casing and having one end connected to the winding drum, the other end projecting through a slit in the casing, a box surrounding the slit in the casing and having a braking surface, a pivoted braking member coöperating with the braking surface and carried by the box, and manually controlled means for actuating said braking member, the braking member being provided with an upwardly and laterally extending impinging end to engage the flexible member.

7. A portable fire escape comprising a cylindrical casing having a braking face therein and provided at its sides with elong-

gated slots, a winding drum, the ends of which project through the slots, a coiled tape normally within the casing and having one end connected to the winding drum, the 5 other end projecting through a slit in the casing, a box surrounding the slit in the casing and having a braking surface, a pivoted braking member coöoperating with the braking surface and carried by the box, and 10 manually controlled means for actuating said braking member, the braking member being provided with an upwardly and laterally extending impinging end to engage the flexible member, the engaging end of the 15 braking member being out of line with the slots in the casing.

8. A portable fire escape comprising a cylindrical casing having a slit in the periphery thereof and having elongated slots in the sides thereof, a flexible tape coiled 20 within said casing and having a free end projecting through the slit in the periphery thereof, a winding drum connected to the other end of said flexible tape and having ends projecting through the slots in the 25 casing, a sling carried by the projecting ends of the winding drum, and manually controlled means exterior of the casing for exerting friction against the tape to control the unwinding of the same within the casing. 30

In testimony whereof I affix my signature.
PIETRO P. VESCOVI.
